UNITED STATES PATENT OFFICE

117,207

DESIGN FOR A HAMMER OR SIMILAR ARTICLE

Walter W. Rector, Cleveland, Ohio, assignor to
The American Fork & Hoe Company, Cleveland, Ohio, a corporation of Ohio

Application January 13, 1939, Serial No. 82,336

Term of patent 14 years

To all whom it may concern:

Be it known that I, Walter W. Rector, a citizen of the United States, residing at Cleveland, in the county of Cuyahoga and State of Ohio, having invented a new, original, and ornamental Design for a Hammer or Similar Article, of which the following is a specification, reference being had to the accompanying drawing, forming a part thereof, in which:

Fig. 1 is a side elevational view of a hammer
showing my new design;

Fig. 2 is a top plan view; and
Fig. 3 is a front elevational view thereof a portion of the handle being broken away for convenience of illustration.

The dominant features of my design are shown in solid lines in the drawing.

I claim:

The ornamental design for a hammer or similar article, substantially as shown and described.

WALTER W. RECTOR.
